ALONZO A. WARNER, OF NEW BRITAIN, CONNECTICUT, ASSIGNOR TO LANDERS, FRARY AND CLARK, OF NEW BRITAIN, CONNECTICUT, A CORPORATION.

GRINDING-MILL.

No. 904,905.

Specification of Letters Patent.

Patented Nov. 24, 1908.

Application filed December 2, 1907. Serial No. 404,811.

To all whom it may concern:

Be it known that I, ALONZO A. WARNER, a citizen of the United States, residing at New Britain, in the county of Hartford and 5 State of Connecticut, have invented certain new and useful Improvements in Grinding-Mills, of which the following is a specification.

My invention relates to improvements in 10 grinding mills, and the main object of my improvement is efficiency in operation, especially with reference to rapid grinding.

In the accompanying drawing: Figure 1 is a face view of the rotary mill disk for my 15 grinding mill. Fig. 2 is a broken out side elevation of my mill with the rotary mill disk removed so as to show the face of the stationary mill disk. Fig. 3 is a like view of the case with both mill disks and the 20 forcer removed. Fig. 4 is a vertical section of portions of my mill on the lines *aa* of Figs. 1 and 2. Fig. 5 is a vertical section of the said mill on the line *yy* of Fig. 4. Fig. 6 is a sectional view of the rotary mill disk 25 on the line *ss* of Fig. 1.

My mill is especially adapted for grinding corn but is found in practice to be very efficient for grinding coffee and spices and the like.

30 The case A, in its general form is what may be called cylindrical as it is adapted for use with a substantially cylindrical feed screw or forcer 6. It may be provided with any suitable or ordinary standard 7 for holding it in place. At the top there is a sub-hopper 8 cast on the case and to this is fitted the main hopper 9, or hopper extension, which is preferably formed of sheet metal. At the delivery end of the case is a flange 10 to which the fixed or stationary mill disk 11 is secured in any proper manner, as for example by bolts 12 and nuts 13. The interior wall for the main portion of the case, particularly between the hopper and the fixed disk, 15 is substantially of a cylindrical form and is of a larger diameter than the periphery of the screw or forcer. The fixed mill disk is mounted on the case eccentrically to the said interior wall. The ends of the points or teeth at the inner edge of the said disk, and the adjacent part of the case serve as the bearing for the delivery end of the forcer, the periphery of the said forcer being fitted to the said bearing. The other end of the

forcer is provided with a journal 23 that 55 takes its bearing in the end wall of the case, which end wall is bored eccentrically to the interior cylindrical wall of the case, so that the lower side of the forcer comes closely to the said interior wall at the bottom of the 60 case, while a space is left between the said wall at the top and sides of the forcer. A central longitudinal feeding rib 14 is formed on the interior of the case at the top of its inner cylindrical wall and similar ribs 15 65 are formed thereon on the two sides, the tops of these ribs and the case at the bottom being fitted to the periphery of the forcer as best shown in Fig. 5. The delivery end of the case is provided with eight longitudinally 70 extended teeth 16 or short ribs with outwardly flaring spaces 17 between the respective teeth. The ends of these teeth are designed to substantially fit the periphery of the forcer. Three of these teeth, namely, 75 those in alinement with the ribs 14 and 15, are formed on the outer ends of the said ribs. The depths of the feeding ribs and of the spaces 17 between the teeth 16 are indicated by broken lines in Fig. 4. The efficiency of the feed depends largely upon the length of the cylindrical portion of the case between the hopper and the fixed disk.

The fixed grinding disk 11 is provided with a central opening surrounding which there 85 are eight longitudinally extended teeth 18 with spaces between, that extend completely through the said disk in the longitudinal direction of the case and form notches through the inner edge of the said disk, the said teeth 90 and spaces being designed as a continuation of the teeth and spaces 16 and 17 of the case, and they have the same relation to the forcer, the disk-like portion of which is within the circle formed by the inner ends of the teeth 95 18 and takes its bearing therein.

The forcer 6 is of an ordinary form of grooved screw, and is provided with a disk-like end 19 that substantially fills the circle inside of the points of the teeth 18 while the 100 grooves in the screw of the forcer run out or vanish at the periphery upon reaching the disk-like end 19, so that all the feed at this point is outside of the diameter of the forcer through the outwardly flaring and longitudinally extended spaces between the respective teeth of the case and fixed disk. This 105 end of the forcer is also provided with a non-

circular disk seat 20, and a screw threaded stem 21 for the attachment of the rotary grinding disk 26 in an ordinary manner, the said disk being secured in place on the forcer 5 by a nut 22. The opposite end of the forcer has a journal 23 that takes its bearing in the end of the case, while an ordinary crank 24 is attached to the outer end of the forcer. As shown there is a pair of ball bearing 10 disks 25 between the crank hub and end of the case, but this is not of my present invention.

The mill disks 11 and 26, are constructed in substantial accordance with my Patent No. 15 782,293, dated Feb. 14, 1905. As in the aforesaid patent the face of each mill disk is divided into several sets of teeth one of which is a long flat topped tooth 27, with a broad face at its inner end and its outer end divided into two finer teeth by means of the groove 28. These flat topped teeth stand up boldly above the teeth on either side thereof. As herein shown there are eight of these long flat topped teeth with intermediate teeth of 25 less projection at their inner ends, while the outer ends of all the teeth at and near the edges of the disks are substantially in one plane to form an annular bearing contact as in the aforesaid patent. The inner ends of 30 these flat topped teeth 27, in the fixed disk 11, as shown in Fig. 2, are formed on the disk faces of the longitudinally extended teeth or points 18, and the spaces between the points are in the form of notches through the inner 35 edge of the disk which notches substantially follow the length of these teeth 27 on one side, for nearly their full depth, and then curve gradually away from the said teeth to the inner end of the next flat topped tooth, 40 so that the inner ends of all the teeth in each set, other than the flat topped teeth, terminate in the spaces between the inner ends of the teeth 27. In the faces of these long and 45 flat topped teeth 27, in both disks, I form recesses or breaks 29 for the better distribution of the material as it nears the outer edges of the grinding disks. I also form breaks 30 towards the inner ends in a plurality of the intermediate teeth of each set in the fixed mill disk in order to give a better hold on 50 the material being ground.

Upon turning the crank, when the mill is supplied with material to be ground, so as to 55 rotate the forcer and rotary disk, the forcer and ribbed case coact to feed the material forwardly towards the delivery end of the case. The forcer substantially wipes the lower part of the inner cylindrical wall of the case so as to force along all the material 60 at the bottom, even that which is quite fine. When the space between the periphery of the forcer and the inner wall of the case above the forcer becomes filled the material therein may be cracked or crushed by the 65 coaction of the feeding ribs and the forcer.

This forcer has an unbroken smooth periphery for continuous action upon the unbroken feeding ribs and any crushing action that it may have is only incidental to the feeding action. As it reaches the grinding disks, the 70 material is forced outwardly and forwardly through the spaces 17 in the end of the case, and spaces between the inner ends of the teeth 27, from which spaces it radiates outwardly and is ground between the toothed 75 faces of the two mill disks. A mill of this construction is a very rapid grinder.

I claim as my invention:

1. In a grinding mill, the combination of a case having an inner cylindrical wall provided with a plain surface at its lower part and feeding ribs at its upper part, with a screw forcer mounted in the said case in bearings arranged eccentrically to the said inner cylindrical wall with its periphery closely approaching the plain surface of the said inner wall and the tops of the several feeding ribs, and mill disks at the delivery end of the said case.

2. In a grinding mill, the combination of a case having an inner cylindrical wall and feeding ribs with a screw forcer having a disk like portion at its delivery end, and a pair of mill disks, one of which is fixed on the case and the other of which is mounted on the delivery end of the said forcer, the said fixed disk having a series of longitudinally extended teeth with outwardly flaring intermediate open spaces immediately surrounding the said disk like portion of the 100 forcer.

3. In a grinding mill, a case having an inner cylindrical wall, a series of teeth with outwardly flaring spaces between at the grinding end of the said case, the said spaces 105 extending outwardly from the said inner cylindrical wall, in combination with a mill disk mounted in a fixed position on one end of the said case, the said disk having its face divided into several sets of teeth one of which teeth in each set is a long flat topped tooth with a broad face at its inner end, a forcer with its end fitted within the circle formed by the longitudinally extended inner ends of the said long flat topped teeth, 110 and a companion mill disk mounted on the outer end of the said forcer, the said fixed disk having open spaces therethrough in the form of notches at its inner edge, the said ends and spaces at the inner edge of the said 115 disk being formed in continuation of the teeth and outwardly flaring spaces at the grinding end of the said case.

4. In a grinding mill, the herein described mill disk having a series of teeth arranged 125 in several sets each set comprising one broad and substantially flat topped tooth and a plurality of finer teeth, the inner end of the said flat topped tooth standing above the tops of the said finer teeth, the face of the 130

said broad and flat topped tooth being broken by a transverse recess extending across the same towards its outer end.

5. In a grinding mill, the herein described mill disk having a series of teeth arranged in several sets, one of which teeth in each set is provided with a broad flat top at its inner end that stands above the tops of the other teeth at their inner ends, the face of 10 the said broad topped tooth being broken by a transverse recess extending across the same towards its outer end, a plurality of the intermediate teeth in each set also being broken towards their inner ends by trans- 15 verse recesses extending across the same.

6. In a grinding mill, the combination of a case having an inner cylindrical wall with a fixed mill disk mounted on one end of the said case, the said disk having an imperforate grinding face inside of its outer edge and having at its inner edge a circular series

of longitudinally extended teeth with intermediate spaces in the form of notches through the said inner edge that flare outwardly from the said inner cylindrical wall 25 of the case, a force having a screw thread and a disk-like end that substantially fills the said circular series of longitudinally extended teeth at the inner edge of the said disk, while the groove in the force runs out 30 at the periphery of the force upon reaching the edge of said disk-like end, thus stopping short of the end face of the said force, and a rotary mill disk mounted on the outer end of the force and having an imperforate 35 grinding face that covers the said open spaces through the inner edge of the said fixed disk.
